UNITED STATES PATENT OFFICE.

ERNEST RUDOLPH UHLIN, OF McDONALD, PENNSYLVANIA, ASSIGNOR OF
ONE-HALF TO BARRETT D. TILLINGHAST, OF McDONALD, PENNSYLVANIA.

VALVE-GEAR FOR EXPLOSIVE-ENGINES.

No. 802,125.

Specification of Letters Patent.

Patented Oct. 17, 1905.

Application filed December 15, 1903. Serial No. 185,261.

To all whom it may concern:

Be it known that I, ERNEST RUDOLPH UHLIN, a citizen of the United States, residing at McDonald, in the county of Washington and State of Pennsylvania, have invented new and useful Improvements in Valve-Gear for Explosive-Engines, of which the following is a specification.

The object of my invention is to provide a new and improved gas-engine, more particularly to provide new and improved means for controlling the admission of gas and air and the escape of spent gases to and from the cylinder of a four-cycle engine.

In the accompanying drawings, which illustrate applications of my invention, Figure 1 is a part side elevational view and a part-sectional view of an engine constructed in accordance with my invention; Fig. 2, a vertical sectional view of controlling-valve and its casing; Fig. 3, a part transverse sectional view and a part plan, the section being taken on line I I of Fig. 2; Fig. 4 a part-elevational view and a part-sectional view showing controlling-valve and its casing applied to the cylinder at a different position from that shown by Fig. 1 and a modified form of mechanism for operating the valve; and Fig. 5, a part plan and a part-sectional view, the section being taken on line II II of Fig. 2.

Referring to the drawings, 1 represents the bed, 2 the cylinder, and 3 the piston, of a four-cycle explosive-engine. The explosive mixture is introduced into the cylinder and the spent gases discharged therefrom through a valve-casing 4, which may be applied to either a horizontal type of engine or to a vertical type and may be connected up with the cylinder in the manner shown by Fig. 1 or in the form of Fig. 4. Valve-casing 4 is provided with a gas-inlet 5, air-inlet 6, and exhaust-passage 7.

A characteristic and important feature of the present invention is the means shown for controlling the admission of the explosive mixture to the cylinder and the escape of spent gases therefrom. For this purpose I employ a single valve in place of several valves, as has heretofore been the practice, thereby greatly simplifying the construction and providing means less liable to cause trouble in operation.

Valve 8, as illustrated and as preferred, consists of a hollow cylinder provided with a head 9, which latter is held on a seat 10 by

spring 11. Valve 8 is also provided with 55 ports 12 and 13, which are adapted to respectively register with an exhaust-port 14 and with gas and air ports 15, formed in the valve-casing. Spring 11 surrounds a stem 16, extending from an end of the valve 8, and is 60 held in position between the outside of the valve-casing and a nut or stop 17 on stem 16. Communication between the interior of the valve-casing 4 and the cylinder is controlled by the head 9 of valve 8, and valve 8 is operated by suitable mechanism connected with main drive-shaft 18. The valve-operating mechanisms, which will be fully hereinafter described, are arranged to effect a movement of valve 8, so that as the head 9 is moved off 70 its seat the exhaust-port 12 of valve 8 will simultaneously register with exhaust-port 14, thus permitting an exhaust from the cylinder through said ports to exhaust-passage 7. After the exhaust is effected a continued movement of valve 8 closes the exhaust-ports and establishes communication between the gas and air supply and the interior of the valve-casing by means of the ports 13 and 15. After 75 the charge of explosive mixture is drawn 80 into the cylinder, which occurs about the time the piston completes its suction-stroke, the valve is returned and communication between the valve-casing and cylinder cut off.

Attention is called to the fact that the gas- 85 inlet is placed a slight distance below the air-inlet, the purpose of this construction being to permit the gas to be cut off in advance of the air upon the return of the valve at the completion of the suction-stroke. This construction is particularly shown by Fig. 2.

The means shown by Fig. 1 for operating the valve comprise a pinion 19, mounted on shaft 18, gear 20, carried on shaft 21, and a cam 22, also carried on shaft 21. Cam 22 is 90 in contact with a roller 23, carried on the end of a rod 24. Said rod 24 is supported by bosses 25. A spring 26 is employed for the purpose of maintaining roller 23 against the cam.

In connection with the valve-operating mechanism I have shown a pick-blade governor comprising blade 27, pivoted weight 28, and spring 29. Blade 27 is normally in contact with valve stem or rod 16, as shown by 105 dotted lines in Fig. 1; but under abnormal speed the weight 28 causes the blade 27 to be brought out of contact with stem 16. In

place of this pick-blade governor other suitable forms of governors may be employed.

In the form of Fig. 4 the valve is operated by a modified form of valve-operating mechanism comprising a revolving shaft 30, worm-gear, (not shown,) cam 31, and connecting-rod 32.

What I claim is—

1. The combination, with an explosive-engine, of means for controlling the admission of an explosive mixture and the escape of spent gases to and from the cylinder, comprising a casing in communication with the cylinder, having a gas-inlet port, an air-inlet port, and an exhaust-port, a single tubular valve closed at its outer end and located within the casing controlling said ports and the communication between the casing and cylinder, and means for operating the valve.
2. The combination, with an explosive-engine, a valve-casing in communication with the cylinder having an air-supply port, a gas-supply port arranged in advance of the air-supply port, and an exhaust-port, a single tubular valve located within the casing and provided with a head for controlling communication between the cylinder and casing, ports in the valve adapted to register with

the ports in the casing, and means for moving the valve whereby communication is first effected between the cylinder and the exhaust-port and upon a further movement of the valve between the gas and air supply ports and cylinder.

3. The combination, with an explosive-engine, a casing having a gas-inlet, an air-inlet, ports in the casing in communication with said inlets, a single tubular valve having its outer end closed and provided with ports arranged to register with said ports for controlling the admission of gas and air to the interior of the casing, an exhaust-outlet, a port in the casing in communication with the exhaust-outlet, a port in the valve arranged to register with the exhaust-port, a head on the valve controlling communication between the cylinder and casing, and means for operating the valve.

In testimony whereof I have signed my name to this specification in the presence of two subscribing witnesses.

ERNEST RUDOLPH UHLIN.
